UNITED STATES PATENT OFFICE.

ALWIN RUCKSTUHL, OF WINTERTHUR, SWITZERLAND.

ROTARY COMPRESSOR.

Application filed December 11, 1925, Serial No. 74,825, and in Germany May 7, 1925.

It is known from experience that with the usual control of rotary compressors provided with stationary distributing channels which only permits a closing of the suction branch and a simultaneous connection of the delivery branch to the surrounding atmosphere very violent and sudden changes in the power absorbed by the compressor occur, which may cause disagreeable troubles in the 5 plants supplying the driving power and may even cause a complete standstill of such plants in case they are comparatively weak. The use of devices effecting a retardation of the movements of the controlling organs 10 does not improve these conditions as the sudden change of load depends on the simultaneous closing of the suction branch and the 15 opening of the delivery branch.

According to the present invention a division 20 of the controlling effect into two phases is contemplated inasmuch as at first the delivery branch is slowly connected to the surrounding atmosphere and the suction branch is slowly closed only after a predetermined pressure is reached in the delivery 25 branch.

A constructional example of a device for carrying into effect this method of controlling a rotary compressor is diagrammatically illustrated on the accompanying drawings, in which:

Fig. 1 is a vertical section of the rotary engine and the controlling gear.

Figs. 2 and 3 show details of the controlling gear in different operative positions.

As is shown in Fig. 1 the rotary compressor is in its normal design provided with a casing 1 in which the drum or rotor 2 containing the gates 3 is eccentrically mounted. The air enters the compressor through the suction branch S and leaves it through the delivery branch or pressure branch D. In the latter a non-return valve 4 is arranged which prevents the compressed air in the conduit 5 from flowing back into the compressor when the controlling action has started. The pressure conduit 5 is further connected to a control relay 7 by means of conduit 6, which relay comprises two small distributing pistons 8 and 9 which may be acted upon by springs or weights and which permit the controlling action to take effect only after a determined pressure in the pressure conduit has been reached. The relay 7 is then connected by the conduit 12 to a receptacle 14 containing a viscous liquid. The latter may

flow through the pipe 15 to act on the piston 16 from below. The piston 16 cooperates with a lever 17 having three arms and the turning movement of the lever causes an operation of the overflow valve 18 arranged in a casing 21. Adjustable screws 23 and 24 are provided on the lever 17 for the purpose of adjusting the moment in which the lever acts upon the valve 18 and the shut-off valve 22. The return movement of the overflow valve 18 is caused by the spring 25 and that of the shut-off valve 22 by the spring 26. The shut-off valve 22 is provided with ports 27 which register with corresponding ports 28 in the casing 21 when the valve 22 is in its uppermost position, in which case the air which is sucked through the suction conduit 29 is permitted to flow to the suction branch S. The casing 20 of the overflow valve 18 is connected on one side to the pressure branch D by the conduit 30 and on the other side to the surrounding atmosphere by means of the pipe 31.

If the desired highest pressure is reached the weights corresponding to this pressure are lifted by the air acting on the piston 8 whereby the conduit 6 and the channel 10 are connected with each other. The air now gets below the distribution piston 9 and lifts the latter and uncovers thereby the pressure equalizing channel 11 and connects the conduits 6 and 12 with each other. The air flows now through the conduit 12 above the liquid level in the casing 14. The controlling means take up the position illustrated in Fig. 2. The compressed air forces the liquid through the pipe 15 to act on the piston 16 from below. The velocity of the liquid flowing through the pipe 15 may be regulated by adjusting the set screw 32 which permits the liquid flow to be throttled and thereby adjust the duration of the controlling action to any requirement. The pressure exerted by the compressed air through the intermediary of the liquid on the lower side of the piston 16 lifts the latter and thereby turns the lever 17. The set screws 23 and 24 are so adjusted that at first the overflow valve 18 is opened and a connection between the pressure branch D and the surrounding atmosphere is effected. The overflow valve 18 is provided with a cone 19 which causes a throttling of the escaping compressed air in order to retard the throwing-off of the load of the compressor. This overflow of air causes the pressure in the

delivery branch to be lowered and the non-return valve to close automatically. As soon as the pressure in the delivery branch D has been reduced in the desired degree the 6 set screw 24 of the lever 17 presses the shut-off valve 22 in the downward direction. In consequence thereof the ports 27 are displaced relative to the ports 28 and in the lowermost position of the valve these ports 10 are altogether separated from each other whereby the suction conduit 29 is separated from the suction branch S and the machine runs as a vacuum pump. The closing of the entrance ports to the suction branch has 15 also to be performed slowly and in a determined manner which is taken into account by the shape of the valve ports 27.

The sequence of the above described movements is reversed when the compressor has 20 to start again. When the pressure in the conduit 5 is lowered by a fraction of one atmosphere the raised distributing piston 8 moves in the downward direction by the influence of the weight whereby the connection 25 between the conduit 6 and the channel 10 is interrupted as is shown in Fig. 3.

This movement, however, does not cause a simultaneous movement of the piston 16, as 30 the pressure below the distribution piston 9 is maintained by the flow of air through the pressure equalizing channel 11. Only when the pressure has dropped to the desired minimum does the distribution piston 9 which is loaded by a corresponding weight return by 35 the action of said weight into its lowermost position and close the pressure equalizing channel 11 and connect the conduits 12 and 13 with each other. The compressed air present above the liquid in the receptacle 14 escapes through the conduits 12 and 13 into 40 the surrounding atmosphere and suspends the pressure below the piston 16. The spring 26 of the shut-off valve 22 and the spring 25 of the overflow valve 18 are then 45 operative and return these parts into their initial positions, whereby the liquid below the piston 16 recedes only slowly on account of the throttling organ 32. Thereafter first of all the shut-off valve 22 and the suction 50 conduit are opened and the compressor is loaded thereby; later on the overflow valve 18 closes the overflow opening and the compressor is again ready for normal working (all the parts being again in the position 55 shown in Fig. 1).

I claim:

1. Mechanism for controlling a rotary compressor comprising in combination, means to connect the delivery of the compressor to the surrounding atmosphere, means to interrupt the suction action, and a pressure responsive device operatively connected to both of said means and causing the first mentioned means to be operative before 60 the second mentioned means to obtain a

gradual reduction in the power absorbed in driving the compressor, and vice versa to obtain a gradual increase in said power, said pressure responsive device becoming operative only after a determined delivery pressure has been reached. 70

2. An arrangement for controlling a rotary compressor having a suction branch and a delivery branch, comprising a non-return valve cooperating with the delivery branch, a cut-off organ cooperating with the suction branch, means to connect the delivery branch to the surrounding atmosphere, a pressure responsive device cooperating with said cut-off organ and with said means, a fluid distributing system connected to the delivery branch and to said device, and loaded distributing pistons controlling said system whereby said pressure responsive device actuates said means and said cut-off 80 organ when a determined pressure in the delivery branch which corresponds to the load on the distributing pistons is reached. 85

3. An arrangement for controlling a rotary compressor having a suction branch and a delivery branch, comprising in combination, a non-return valve cooperating with the delivery branch, a cut-off organ cooperating with the suction branch, means adapted to connect the delivery branch to the surrounding atmosphere, a valve interposed in said means, a pressure responsive device including a receptacle containing a liquid and a piston displaceable by said liquid to cooperate with said cut-off organ and with said valve, a fluid distributing system connected to the delivery branch and to said device, and two loaded distributing pistons controlling the flow of fluid in said system whereby said pressure responsive device actuates said valve and said cut-off organ when a determined pressure in the delivery branch which corresponds to the load on the distributing pistons is reached. 95 100 105

4. An arrangement for controlling a rotary compressor having a suction branch and a delivery branch, comprising in combination, a non-return valve cooperating with the delivery branch, a cut-off organ cooperating with the suction branch, means to connect the delivery branch to the surrounding atmosphere, a valve interposed in said means, a pressure responsive device including a receptacle containing a liquid, a piston displaceable by said liquid and a three armed lever to cooperate with said piston, said cut-off organ and said valve, two relay cylinders one of which being connected to the delivery branch and the other being connected to the receptacle of said pressure responsive device, a plurality of interconnections between said cylinders, and two loaded distributing pistons for controlling said connections and thereby the flow of fluid whereby said pressure responsive device ac- 110 115 120 125 130

tuates said valve and said cut-off organ when a determined pressure in the delivery branch which corresponds to the load on the distributing pistons is reached.

- 5 5. An arrangement for controlling a rotary compressor having a suction branch and a delivery branch, comprising in combination, a non-return valve cooperating with the delivery branch, a cut-off organ co-operating with the suction branch, means to connect the delivery branch to the surrounding atmosphere, a valve interposed in said means, a pressure responsive device including a receptacle containing a liquid, a 10 piston displaceable by said liquid, a three armed lever to cooperate with said piston, said cut-off organ and said valve, adjustable means on said three-armed lever to time the cooperation of said lever with said cut-off organ and said valve, and throttling means 20 for adjusting the action of the liquid on said piston, two relay cylinders one of which is connected to the delivery branch and the other connected to the receptacle of said pressure responsive device, a plurality of 25 interconnections between said cylinders, and two loaded distributing pistons for controlling the flow of fluid through said connections when a determined pressure in the delivery branch which corresponds to the 30 load on the distributing pistons is reached.

In testimony whereof, I have signed my name to this specification.

ALWIN RUCKSTUHL.
